UNITED STATES PATENT OFFICE.

ALVIN D. KEENE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed April 24, 1925. Serial No. 25,615.

My invention relates to electric furnaces and particularly to resistor-supporting means for such furnaces.

One object of my invention is to provide a relatively simple and compact, removable, resistor-supporting means that is interlocked with a wall of the furnace, in combination with a holding means therefor that is held in place by a resistor member.

10 In practicing my invention, I provide a resistor-supporting member having an inner portion adapted to interlock with a wall of a furnace and a holding means for said supporting means that is held in proper operative position by a resistor carried by said supporting means.

In the drawings,

Figure 1 is a view, in vertical longitudinal section, of a furnace embodying my invention;

Fig. 2 is a view, in side elevation, of a resistor-supporting member embodying my invention;

Fig. 3 is an end view thereof;

25 Fig. 4 is a top plan view thereof;

Fig. 5 is a top plan view of a holding means operatively associated with the resistor supporting member illustrated in Figs. 2 to 4, inclusive;

30 Fig. 6 is a view, in vertical longitudinal section, of a modified form of furnace embodying my invention;

Fig. 7 is a fragmentary horizontal sectional view therethrough taken along the line 35 7-7 of Fig. 6;

Fig. 8 is a view, in perspective, of a resistor-supporting member embodying my invention, and

Fig. 9 is a view, in perspective, of a holding means operatively associated with the resistor supporting member illustrated in Fig. 8.

40 Referring more particularly to Figs. 1 to 5 of the drawings, an electric resistor furnace 11 comprises a plurality of bricks or blocks 12, of a suitable refractory electric-insulating material so arranged as to constitute a plurality of walls enclosing a furnace chamber 13. The bricks or blocks 12 are so shaped and disposed as to provide a furnace chamber of any suitable or desired contour and dimensions, here shown as substantially rectangular in section.

50 As the device embodying my invention and to be hereinafter described in detail, may be

associated with any usual construction of furnace of this type, the furnace proper is not further illustrated or described in detail. It is, however, provided with all other devices usually provided for furnaces of this type and comprising doors with charging means, etc., as may be required by the method of operation of the furnace.

Each of the walls that is to have an extended resistor member associated therewith and supported thereby, is provided with a horizontal groove or slot 14 that is of substantially L-shape in lateral section as is more particularly shown in the two side walls of the furnace 11 in Fig. 1 of the drawing.

A resistor-supporting member or hanger block 15 is made of a refractory electric-insulating ceramic material. The member 15 is of substantially L-shape in longitudinal section, that is, it is provided with a lateral extension 16 at the rear end thereof, which rear end portion is adapted to fit into the slot or groove 14. The front end of the member 15 is adapted to extend into the furnace chamber 13 and is provided with a laterally-extending groove 17 upon which may be located a resistor member 18. The resistor member 18 is here shown a flat ribbon of a suitable metallic resistor material, such as nichrome, that is preformed to comprise a plurality of substantially straight and parallel-extending convolutions substantially as illustrated in Fig. 1 of the drawing. The resistor member is adapted to be suspended by the upper loops thereof from a plurality of spaced resistor-supporting members 15. While I have illustrated the hanger blocks 15 as formed to support a resistor ribbon, they may be adapted to support a rod or wire or a tubular resistor member, in which case the portion 17 is made shorter than illustrated in Fig. 2 of the drawing.

A lateral projection 19 is provided at the front end of the member 15 and is integral therewith for preventing movement of the resistor member 18 longitudinally of the member 15.

55 A refractory holding member 21 is operatively associated with each of the supporting members 15 and may be of the same width as the body portion thereof and is adapted to be located beneath the member 15.

In placing the supporting members in their proper operative position within the

groove or slot 14, the member 15 is first moved into position in a direction laterally of the face of the furnace wall and is then moved in a direction longitudinally relatively thereto, which locates the projection 16 in the lateral extension of the groove 14, substantially as illustrated in Fig. 1 of the drawing. The member 21 is then placed beneath the member 15 whereby the latter is maintained in interlocked position within the groove 14 and relatively to the wall of the furnace. The length of the member 21 is such that it extends from the rear end of the groove 14 to a point immediately back of the rear edge of the resistor member, whereby it is held in its proper operative position by the resistor member.

While I have indicated, in Fig. 1 of the drawing, that the resistor-supporting members 15 are to be separated by individual blocks 22, this construction is not essential as the horizontal width of the members 15 may be made such, especially at the rear portion thereof, that the sides thereof will be in operative engagement and no spacing blocks 22 would then be required.

A plurality of properly spaced and aligned lugs 23 are provided to space the bottom loop portions of the resistor member from each other, as is illustrated in Fig. 1 of the drawings.

Referring more particularly to Figs. 6 to 9 inclusive of the drawings, a modified form of device embodying my invention is there illustrated. Resistor-supporting members 24 are there provided and may be made of relatively thin material, such as nichrome, each member 24 having an integral lateral extension 25 at the rear end thereof. The front end thereof is adapted to project into the furnace chamber 13 and is provided with a notch 26 in its upper portion to receive a resistor member 18, here illustrated as a flat ribbon of nichrome that is preformed to comprise a plurality of straight and parallel-extending convolutions as was hereinbefore described in connection with Fig. 1 of the drawing.

The furnace structure is substantially the same as was hereinbefore described and those walls that are to receive and support a plurality of spaced resistor supporting members are respectively provided with a plurality of relatively narrow openings 27 therein, that are of substantially L-shape in horizontal section. The projection 25 of the member 24 is adapted to fit into the lateral extension or projection in an opening 27 as is illustrated more particularly in Fig. 7 of the drawing. The member 24 is moved into its proper operative position by a movement that is substantially at right-angles to the surface of the furnace wall in which it is to be mounted and a single movement in a direction longitudinally thereto. A holding

bar 28 is then placed in the opening 27 at one side of the member 24 and maintains the member 24 in its interlocked position in the opening 27. The length of the member 28 is such that it projects a short distance beyond the face of the furnace wall and is operatively engaged by the resistor member which maintains it in the opening 27, whereby the resistor supporting means and the holding means therefor are held in their proper operative positions relatively to the furnace wall.

While I have illustrated the resistor supporting member 24 as being located in a substantially vertical position with the integral projection 25 extending in a horizontal direction, I do not desire to be limited thereto as the projection 25 may be so located as to project in a vertical direction either upwardly or downwardly as desired.

Lugs or projections 23 may be provided to properly space the resistor portions apart at the bottom end thereof as was hereinbefore described in connection with Fig. 1 of the drawings.

Although the part 15 has been designated as the resistor-supporting member and the part 21 as the holding member, yet, looking at my invention from another viewpoint, the parts 15 and 21 taken together, may properly be considered as constituting a two-part resistor-supporting means, since they co-operate to support the resistor. Likewise, the parts 24 and 28, taken together, may be considered as a two-part resistor-supporting means.

It may be noted that the device embodying my invention provides a plurality of spaced resistor-supporting members that may be made either of a ceramic electric-insulating material or that may be made of a metal and as may be found suitable or desirable, and that these members are located and supported by a wall of a refractory electric insulating material of such material and construction as to prevent a grounding or a short circuit of the resistor member itself. The resistor-supporting means are respectively interlocked with the wall and are held in their proper operative positions relatively thereto by means that are respectively held in their proper operative positions by a resistor member supported by the resistor-supporting means.

While I have illustrated the device embodying my invention as supporting a depending resistor member its use is not restricted thereto as it may be employed with other forms of resistor members that may, for instance, extend in a substantially horizontal direction.

Various modifications may be made in the device embodying my invention without departing from the spirit and scope thereof and all such modifications are in-

tended to be covered by the appended claims.

I claim as my invention:

1. In an electric furnace, the combination with a furnace wall, a resistor-supporting member supported by said wall, and a resistor supported by said member, of means for holding said resistor-supporting member in its proper operative position in said wall, said holding means being prevented from longitudinal movement by said resistor member.

2. In an electric furnace, the combination with a furnace wall provided with a slot, of a resistor-supporting member extending into said slot and having interlocking engagement with one side thereof, a resistor supported by said member, means engaging one surface of said supporting member for maintaining said supporting member in proper operative position, said means being maintained in proper operative position by said resistor.

3. In an electric furnace, the combination with a furnace wall having a slot, of a resistor-supporting member, having interlocking engagement with the sides of said slot, an elongated member for maintaining said resistor-supporting member in proper operative position, a resistor supported by said member, said elongated member being prevented from longitudinal movement by the resistor.

4. In an electric furnace, the combination with a furnace wall, and a resistor member located adjacent thereto, of a resistor-supporting member movable into its proper operative position into said wall by a lateral and then a longitudinal movement thereof relatively to the face of said wall, and means for holding the resistor-supporting member in its proper operative position in

said wall, said holding means being held in operative position by said resistor member.

5. In an electric furnace, the combination with a furnace wall having a slot, of a resistor member, and a two-part removable resistor-supporting means, the two parts thereof being insertable into proper operative positions in said slot in predetermined sequence and being held in said operative positions by the resistor member.

6. In an electric furnace, the combination with a furnace wall provided with an opening therein, of a resistor-supporting member extending into said slot and having interlocking engagement with the sides thereof, a resistor supported by said resistor-supporting member, and means extending alongside of said resistor-supporting member for maintaining it in said interlocking engagement.

7. In an electric furnace, the combination with a furnace wall having a slot of L-shape, of a resistor-supporting member of L-shape, having interlocking engagement with said slot and means for holding the resistor-supporting member in its proper operative position in said wall.

8. In an electric furnace, the combination with a furnace wall having an opening therein, a resistor-supporting member fitting into said opening and having interlocking engagement with the wall, a locking bar substantially co-extensive with the resistor-supporting member and engaging one face thereof, and a resistor member supported by the resistor-supporting member and effective to hold the locking bar in the opening.

In testimony whereof, I have hereunto subscribed my name this 20th day of April, 1925.

ALVIN D. KEENE.
